Inventor
PERCY M. THORN
By his Attorney, Charles H. Wilson.

UNITED STATES PATENT OFFICE.

PERCY M. THORN, OF NEW YORK, N. Y.

GAME.

Application filed March 3, 1922. Serial No. 540,706.

To all whom it may concern:

Be it known that I, PERCY M. THORN, residing at New York, in the county and State of New York, have invented certain new and useful Improvements in Games, of which the following is a specification.

This invention relates to games, and one of the objects is to provide a game capable of being played by two or more players, 10 which is very interesting, and which is also valuable as an advertising medium.

Other objects and aims of the invention, more or less specific than those referred to above, will be in part obvious and in part 15 pointed out in the course of the following description of the elements, combinations, arrangements of parts and applications of principles, constituting the invention; and the scope of protection contemplated will 20 be indicated in the appended claims.

In the accompanying drawing, wherein I have shown a preferred form of embodiment of my invention:

Figure 1 is a plan view of a card, showing my improved game.

Figure 2 is a plan view showing a device employed in playing the game; and

Figure 3 is an elevational view showing the "men" or markers which are used in 30 playing the game.

Referring now to the drawing, the reference numeral 1 indicates the base or foundation upon which the device or game is printed. The reference numeral 2 indicates 35 in the present instance a circular space which is designated "home", the same preferably bearing a representation of a residence or house, and 3 indicates another circular space preferably bearing the representation of a store, which in the present 40 instance is designated "John Doe".

The circular spaces 2 and 3 are preferably connected by a double line 4, which is divided into a plurality of circular spaces 45 5, said lines preferably bearing the barbs 6 of arrows to indicate the direction of travel.

Spaces 5 disposed along the lines 4, may be employed to indicate the imaginary 50 streets which would have to be crossed by a person travelling from the space marked 2 to the space marked 3. Leading from the space 3 is a double line 7, which travels downwardly substantially midway of the 55 height of the card, thence inwardly as at 8, thence upwardly as at 9, thence laterally

as at 10, thence downwardly as at 11, thence laterally as at 12, thence downwardly as at 13, thence laterally as at 14, and thence upwardly as at 15, where it leads to the space 60 indicated at 2.

At this point it may be noted that the space enclosed by the above described line is in the present instance intended to represent a department store, the part indicated generally at A representing the store proper, which may comprise several floors, the space marked B being indicative of the basement of the store.

Located at spaced intervals along the entire line are circular spaces 16, and located intermediate these circular spaces are squares 17, each of which bears a number. Thus the squares in the present instance are numbered from 1 to 45 consecutively, the 70 numbers proceeding in regular order from the space 3 to the space 2. Other characteristic marks are located at various intervals along a devous line heretofore described, which travels from the space 3 to the space 80 2. These marks in the present instance are indicated by the reference numerals 18, 19, 20 and 21. Every space along the aforesaid devous line, as indicated by the circular spaces 16, the numbered squares 17, or the 85 characteristic marks 18 to 21 inclusive, is in the present instance intended to represent aisles of the store.

Located between parts of the line 9 and 11 is provided a space C, which contains a 90 column of numbers in the present instance ranging from 1 to 45 inclusive, to correspond with the numbers provided in the aforesaid devous line, and opposite each of these numbers appears a legend, some 95 of which appear in the drawing. The characteristic marks 18 to 21 inclusive are also positioned in this space, and have located opposite them legends such as shown in the drawing.

It will be understood that in the game as finally arranged, suitable legends will be located opposite each of the numbers provided in the space C, some of them having been omitted in the present instance in the 105 interests of clearness of the illustration.

In Figure 3 of the drawing I have illustrated certain characteristic "men" or markers which may be utilized in playing the game. Thus the reference numeral 22 may 110 indicate a child, 23 a mother of the child, 24 the father; it being understood, of course,

that other characteristic "men" or markers may be provided indicative of other fanciful persons. For instance, markers may be provided to indicate fanciful well known artificial personages known in the advertising field.

The reference numeral 25 indicates a base member or card bearing a circular row of numbers, preferably ranging from 1 to 10 inclusive, and the reference numeral 26 indicates a hand or "spinner" which may be spun by the players, so that the arrow will come to rest at various angular positions upon the card, as will be obvious.

15 Various spaces, such as at D may be provided within the space enclosed by the aforesaid devious line, in which spaces may be provided advertisements of the various goods dealt in by the store.

20 Having thus described the construction of the game which forms the subject matter of my invention, the manner of playing the same may now be understood.

It may first be noted that the present 25 game is primarily intended to be put out as an advertising medium for a store or a place of business handling a line of various commodities, such for instance as a department store. It may for instance be published in a daily newspaper as an advertisement for the store, being changed from day to day, or from week to week, in order to bring the different commodities handled by the establishment to the attention of prospective purchasers. It may also be distributed by the store to purchasers.

The winner of the game is the person who, after moving his marker from the "home" position to the store, and then along 40 the devious line heretofore described, stopping at the various spaces, which spaces are determined by the spinning of the arrow or hand 26 upon the dial 25, accumulates the largest amount of purchases, that is to say, the one who, following the directions 45 determined by the various positions to which his man or marker will be moved, purchases goods or commodities of the greatest money value as determined by the 50 prices of the commodities purchased. It is intended that the persons playing the game, or their friends, or members of their family, in this way will be brought into closer touch with the store or establishment putting out 55 the game, and the business of this store or establishment increased in this manner.

In playing the game, each of the competitors is furnished with one of the "men" or markers, and the contestants operating 60 the spinner or arrow 26 in alternation, each contestant moving the men or marker along the devious line, the number of spaces indicated by the number to which the arrow 65 points when the latter comes to rest, after being spun by a contestant.

Whenever one of the "men" or the markers is moved to one of the numbered spaces or space indicated by one of the characters 18 to 21 inclusive, the contestant whose marker had stopped at one of said spaces, 70 turns to the table appearing under the word "Directions", and follows the instructions set forth in the legend opposite to the number or character upon which his marker is positioned, making the imaginary purchases 75 indicated, and writing the sums of the various purchases in a column, each contestant of course having a separate column.

When the game has been completed and the markers moved throughout the entire 80 extent of the aforesaid devious line, the numbers composing the columns of each of the contestants are added up together, and the contestant having the highest sum of the imaginary purchases is the winner of 85 the game; it being obvious of course that each contestant may play with two or more imaginary persons. For instance a child may take his mother or father on the aforesaid imaginary shopping tour; the other 90 contestant taking the remaining parent or relative with him, it being understood of course that each contestant will play with an equal number of markers.

Moreover, as above indicated, other markers may be provided whereby any number of contestants may play the game, the men or markers being differently colored, or differently shaped, so that each contestant will be able to select and maintain his own 100 man or marker. During the playing of the game, the attention of the contestant is of course directed to the various advertisements which appear along the devious line along 105 which his man or marker is moved during the progress of the game.

It will accordingly be seen that I have provided a game which is not only of great interest, but which may be also of great advertising value while in the present instance the game is shown as adapted to a 110 department store, other variations may be readily provided, whereby any merchant desiring to advertise his goods may utilize it for his benefit.

Another feature of the game which lends interest thereto is that in certain of the legends, provided the contestant is allowed to make selective purchases, the amount specified not being determined. For instance, 120 when a contestant realizes that he is ahead in the game, and his marker is moved to a square which permits of selective purchases, he may take the chance of purchasing something he particularly desires at a lower 125 marked price without endangering his chances of winning the game.

As many changes could be made in this construction without departing from the scope of the following claims, it is intended 130

that all matter contained in the above description or shown in the accompanying drawing shall be interpreted as illustrative only and not in a limiting sense.

5 Having thus described my invention what I claim as new and desire to secure by Letters Patent is:

1. In a game of the class described, the combination with a base member, of a home 10 station thereon, a devious line starting at said home station and returning thereto in a closed path, a plurality of stations along said line, one of which is indicative of a department store or like establishment, the 15 others indicating various departments of said store, a plurality of markers adapted to be moved from said home station along said line, an indicator to control the progress of said markers along said line from 20 station to station, a series of compartments on said base member adjacent said stations, and having listed thereon items of merchandise, and a chart mounted on said base and having indicia thereon to indicate the purchases made in each department, and also 25 further to control the movements of said markers.
2. In a game of the class described, the combination with a base member having a 30 home station thereon, and a closed devious line passing through said home station, and a plurality of other stations indicative of the departments of a department store, or like establishment, of a series of compartments 35 sub-dividing the space within said devious line, each of which compartments represents one of the departments of said establishment, and is provided therein with a list of items of merchandise, each of said compart-

ments being represented by a station on said 40 line, a plurality of competing markers movable in turn from station to station along said line, a rotatable indicator to control the primary steps in the progress of said markers, and a chart mounted on said base member, and having indicia thereon appropriate to each station, said indicia controlling the secondary movement of said markers.

3. In a game of the class described, the combination of a base member, of a home 50 station thereon, a closed devious line passing through said home station, and a plurality of other stations on said line, some of said stations being indicative of a department store or like establishment, and of the various 55 departments therein, a plurality of lines subdividing the space enclosed by said devious line into a series of compartments representing departments of said store, each of said compartments being represented by a 60 station, a plurality of competing markers of diverse form movable along said line from station to station, a rotatable indicator to control the primary steps in the progress 65 of said markers along said line, and a chart on said base member having indicia thereon corresponding to said stations, and thereby 70 said departments, the indicia of said chart representing purchases on said departments and also controlling the secondary steps in the movements of said markers.

In testimony whereof, I affix my signature in the presence of two witnesses.

PERCY M. THORN.
